UNITED STATES PATENT OFFICE.

ERASMUS D. WILT, OF PITTSBURG, PENNSYLVANIA.

DESIGN FOR A BADGE.

SPECIFICATION forming part of Design No. 12,963, dated June 6, 1882.

Application filed April 11, 1882. Term of patent 7 years.

To all whom it may concern:

Be it known that I, ERASMUS D. WILT, of Pittsburg, in the county of Allegheny and State of Pennsylvania, have invented a new and useful Improvement in Designs for Badges; and I do hereby declare the following to be a full, clear, and exact description thereof, reference being had to the accompanying drawings, in which—

10 Figure 1 is a plan view of my improved design for a badge. Fig. 2 is a like view of the design as a badge for the "Knights of Labor" society.

15 My improved design consists of a badge formed of a circle or ring, *a*, within which is a triangle, *b*, the space *c* between the ring and the sides of the triangle being open. Upon this device may be placed the distinctive words or initials which indicate the particular purpose or society for which it is used as a badge. I illustrate this in the drawings as follows: Upon the face of the triangle is the device in monogram "K. of L."

This badge may be of any suitable material—
as gold, silver, or plated metals—and may be 25 formed by stamping, molding, or engraving, as is desired. It may be fastened by a pin or be attached to the ribbon *d*, at the other end of which is a pin or other fastening device. The initials "K. of L." may be plain or other 30 form of letters arranged inside of the triangle, or the initials, name, or legend of the society may be inscribed or engraved on the ring or on the triangle.

What I claim, and desire to secure by Letters Patent, is—

A design for a badge, consisting of a circle or ring, within which is a triangle containing in monogram the characters "K. of L." substantially as shown and described.

40 In testimony whereof I have hereunto set my hand.

ERASMUS D. WILT.
